UNITED STATES PATENT OFFICE.

JAMES H. SAGER, OF ROCHESTER, NEW YORK, ASSIGNOR TO J. H. SAGER COMPANY, OF ROCHESTER, NEW YORK, A CORPORATION OF NEW YORK.

BUMPER.

1,348,962.

Specification of Letters Patent. Patented Aug. 10, 1920.

Application filed May 29, 1920. Serial No. 385,113.

To all whom it may concern:

Be it known that I, JAMES H. SAGER, a citizen of the United States, and resident of Rochester, in the county of Monroe and 5 State of New York, have invented certain new and useful Improvements in Bumpers, of which the following is a specification.

The present invention relates to bumpers and more particularly to the type designed 10 for attachment to motor vehicles, an object of this invention being to provide a construction which will be strong and durable in use and will at the same time be adapted to absorb a large number of the 15 blows received at the front or the rear of the machine.

To these and other ends the invention consists of certain parts and combinations 20 of parts, all of which will be hereinafter described, the novel features being pointed out in the appended claims.

In the drawings:

Figure 1 is a fragmentary plan view of one side of the bumper;

25 Fig. 2 is a detail view showing the manner in which an anchoring member is secured to the curved end of a side bar of an automobile;

Fig. 3 is an enlarged section on the line 30 3—3, Fig. 1;

Fig. 4 is a fragmentary rear view of one end of the bumper;

Fig. 5 is a section on the line 5—5, Fig. 4; and

35 Fig. 6 shows, on a reduced scale a complete bumper attached to two side bars.

Referring more particularly to the drawings, 1 indicates the front bar which in this instance, is formed from a strip of spring 40 metal, preferably curved forwardly. This bar is supported by a supporting means including two separate supporting devices, each comprising, preferably, an anchoring 45 piece 2 secured in any suitable manner to a side bar 3 of the motor vehicle as for instance in the manner described in my U. S. Patent No. 1,267,458 granted May 28, 1918. This anchoring piece has at its forward end channels 4 on opposite sides and in these 50 channels are received the inner ends of two arms 5 and 6 formed of spring metal, these arms being preferably held in the channels by means of bolts 7. The arm 5 is bent outwardly and is secured near the other end of 55 the bumper bar 1 while the arm 6 is bent

inwardly and is secured near the center of the bumper bar 1.

Preferably the arm 5 has a loose or sliding connection with the bumper bar 1 and to this end the ends of the bumper bar 1 are turned 60 inwardly at 7^a on the rear face of the bumper bar and in spaced relation to the latter so that the outer end of each arm 5 lies between the front portion of the bumper bar and the portion 7^a. In order to permit a 65 free movement between the arm 5 and the bumper bar, the arm 5 is preferably provided with a longitudinally extending slot 8 and a bolt 9 is passed through the slot and also through the front portion of the bumper 70 bar and the end portion 7^a, thus holding the end portion against spreading away from the front portion and at the same time confining the end of the arm 5 while permitting relative movement between said arm and the 75 bumper bar 1. The outer end of the arm 6 is preferably loosely secured to the bumper bar 1 by a clip or collar 10.

This construction of a bumper permits of the inexpensive manufacture thereof, as no 80 large bending appliances are required. Each supporting device embodies two separate arms which are secured to an anchoring piece preferably by bolts which hold the arms firmly clamped to opposite sides of 85 the anchoring piece. One of these arms is deflected outwardly while the other is reflected inwardly, the inwardly deflected portion being preferably rigidly secured to the front bar near the center of the latter and 90 the outwardly deflected portion being preferably loosely secured to the front bar near the outer end of the latter, the front bar preferably having its ends bent inwardly on the rear face of such front bar to cover 95 the ends of the outwardly deflected arms of the supporting means.

What I claim as my invention and desire to secure by Letters Patent is:

1. A bumper comprising a front bar 100 formed of a spring strip with its ends turned inwardly on its rear face, and supporting means comprising two arms formed of spring stock and each deflected outwardly and secured under the inwardly 105 turned end of the front bar.

2. A bumper comprising a front bar 110 formed of a spring strip with its ends turned inwardly on its rear face, and supporting means comprising two arms formed of spring

2
stock and each deflected outwardly and loosely secured under an inwardly turned end of the front bar.

3. A bumper comprising a front bar 5 formed of a spring strip with its ends turned inwardly on its rear face, bolts connecting said inwardly turned ends with the front portion of the front bar, and supporting means comprising two arms formed of spring stock and each deflected outwardly, each of said arms being provided with a slot near its free end through which the bolt extends, the end of each arm lying between an inwardly turned end and the front 10 portion of the front bar.

4. A bumper comprising a front bar, and supporting means comprising two pairs of arms, each arm being formed of a spring strip, one member of each pair being turned 15

outwardly and being loosely secured to the 20 front bar near the end of the latter, and the other being turned inwardly and being secured to the front bar adjacent the center of the latter.

5. A bumper comprising a front bar, and 25 supporting means comprising two anchoring pieces, each provided with channels on opposite sides, and two pairs of spring arms, each pair having their inner ends bolted in the channels of an anchoring piece, one 30 member of each bar being deflected outwardly and being secured to the front bar near the end of the latter, and the other member of each pair being deflected inwardly and being secured to the front bar 35 near the center of the latter.

JAMES H. SAGER.
